UNITED STATES PATENT OFFICE.

ROLLYN H. BAKER, OF DAYTON, OHIO, ASSIGNOR TO THE BAKER MANUFACTURING COMPANY, OF DAYTON, OHIO, A CORPORATION OF OHIO.

COIN-CONTROLLED VENDING MECHANISM.

Application filed February 24, 1922. Serial No. 538,941.

This invention relates to coin controlling operated mechanism for dispensing and other devices, and its objects are such as will be hereinafter set forth.

5 The present application is in part a continuation of my application Serial Number 241,131, filed June 21, 1918. In said application the mechanism which constitutes part of the subject matter of the present application, 10 is associated with a machine for vending cups and drinks. It consists, briefly, in a crank whereby the vending machine is operated, and mechanism for locking the crank against rotation until after a coin of suitable proportions has been inserted in a slot. The present 15 application also discloses mechanism for the same purpose, which is an improvement over that shown in my former application. While this improvement differs considerably from 20 the former device in details of construction, in the broader aspect the two structures are substantially the same, and for that reason they will be the subject of certain broad claims. The improved structure will also be 25 the subject of certain specific claims.

The principal object of my invention is to provide a coin controlled mechanism for operating dispensing and other devices which will be strong, simple of construction and 30 free from parts that are liable to be injured or disabled by the severe and abusive use to which mechanism of the kind is commonly subjected.

Another object is to eliminate as far as 35 possible the liability to derangement or injury by malicious or mischievously inclined persons; also to reduce as far as it is practicable the possibility of operating the mechanism without first inserting a coin of the required 40 kind in the receptacle provided for the purpose; also to provide for returning coins to the operator in case they fail to release the device.

Another object is to provide a device whose 45 various functions are effected by positive means, instead of depending upon the weight of a coin or other equally delicate and uncertain mechanism.

Another object is to provide for registering 50 the coins which actually pass through the machine to the cash box, but to allow the machine to be operated by the caretaker without the use of a coin and without the register being actuated. Other objects will be obvious 55 or particularly pointed out hereinafter.

In the accompanying drawings,

Figure 1 is a reproduction of Figure 8 of my application Serial Number 241,131, and is a right side elevation of the principal part of the cup and beverage vending device shown 60 in said application.

Figures 2 and 3 are reproductions of Figures 12 and 13, respectively, of Serial Number 241,131, and show parts of the mechanism seen in Figure 1 in different positions. Figure 2 shows the position which certain parts assume in case the crank 32 in Figure 1 is operated without a coin having been inserted, or if a coin of deficient size has been inserted. Figure 3 shows a certain stage of operation 70 of the parts when a coin of proper size has been inserted and the crank turned a short distance.

Figure 4 is a right side elevation of the improved mechanism for doing the work of 75 the mechanism shown in Fig. 1. In this view the parts are in normal position.

Figure 5 is a view similar to Fig. 4, but with the parts in the position they would assume were the crank (not shown in this 80 figure) moved without a suitable coin having been inserted in the slot.

Figure 6 is a fragmental view on line 6-6 of Figure 5.

Figure 7 is a view of parts shown in Figures 4 and 5, just after the full stroke device has taken control of the crank shaft but before the coin is ejected from the coin carrier.

Figure 8 is a fragmental view showing the operation of the counter by the coin.

Figures 9, 10 and 11 are successive stages of operation of the coin actuated mechanism and the coin ejector.

Figure 12 is a fragmental plan view, showing the relation of the coin receptacle to the 95 enclosing hood, showing the facility with which a coin may be inserted in the receptacle.

Referring now to Figure 1, I shall review briefly the vending device, so that the requirements for a mechanism to operate it will be better appreciated. At the bottom of Figure 1 is shown a portion of the base plate 25 which carries the mechanism above. This plate acts as a cover for the reservoir which contains the beverage to be sold. Attached to the under side of this plate is a pump, whose piston rod is attached to a rack 26. Meshed with the rack is a gear 27, loosely mounted on a transversely extending shaft 28. Fixed to 100

the shaft in juxtaposition to the gear is a disk 29 which is provided with an arcual slot 30. A stud 31 fixed in the gear extends through this slot and a short distance past the disk. 5 The reservoir, pump and piston are not shown.

The shaft is rotated forward and backward manually by means of a crank 32. Turning the crank clockwise as it is seen in Figure 1, first rotates the disk 29 idly, but when the 10 lower end of the slot 30 impinges on the stud 31 the gear 27 is made to rotate with the shaft, and thus the rack is lifted, the pump piston being simultaneously lifted. Counter clockwise motion of the crank moves the rack 15 downward after the upper end of the slot 30 has impinged on the stud 31. The slot therefore affords a limited lost motion between the rack and crank, the purpose of which will appear presently. The shaft 28 is journaled in 20 a pair of side frames 33, one of which is seen in the figure. At their upper ends these frames carry a super base 34, on which is carried a cup dispensing device 35 and a stack of nested cups 36. The lower end of the stack 25 of cups hangs down in a compartment which is formed by a semi-circular wall 37 and a pair of segmental doors 38, which are mounted to swing in opposite directions on a common vertical axis. By means of a lever 39 pivoted 30 at 40 to the superbase 34, and a cam (not shown) on shaft 28, the doors are opened when the crank is moved clockwise. This same motion of the crank releases the bottom cup, so that the operator may remove it 35 from the stack. He then sets the cup on the floor of the compartment under the spout (not shown) and returns the crank to its normal position, as seen in Figure 1. The forward or clockwise stroke of the crank 40 caused the pump cylinder to be filled with liquid from the reservoir and on the return stroke of the crank this liquid is discharged from the cylinder into the cup. By means of mechanism it is not necessary to describe, 45 the door is held in its open position, as in Figure 1, until the cup has been removed from the compartment. The door then closes itself, which completes the cycle of operation.

I will now describe the mechanism shown 50 in Figures 1, 2 and 3, for preventing operation of the crank unless a coin of required size has been deposited in the coin chute. It is understood that the mechanism shown in Figure 1 is to be enclosed by a hood. This 55 hood is provided with a slot which registers with a chute 50, whereby a coin is carried to a coin carrier 51 mounted on the disk 27. This carrier is a small lever or pawl, pivoted at 52 to the disk 29. A spring 53 presses the 60 pawl toward the perimeter of the disk, its movement in that direction being limited by a tail 54 on the pawl impinging on a pin 55 set in the disk. The pawl 51 is separated from the disk by a washer (not shown) 65 rounding the pivotal screw 32, a sufficient dis-

tance to provide a space between the disk and pawl adapted to receive a coin. An inwardly bent lug 56 on the pawl acts as a temporary support for the coin. In the same vertical plane with the coin as it reposes in 70

the carrier, is a chute composed of two parallel plates 57. These plates extend upward and at the level of the shaft's axis carry a screw 58, the end of which acts in the beginning as a support for the coin. In Figure 1 a coin is shown with dotted lines, confined between the pawl and disk, and resting on end of the screw 58 and the lug 56.

Loosely mounted on the shaft 28 is a lever 60, one end of which is connected by a link 61 to a locking member 62. This member is a lever mounted to rock on a fixed center 63, and is provided with a hook 64, which, when the lever is rocked to the position it occupies in Figure 2 is adapted to catch the stud and 80 arrest the gear 27. The lever 60 is placed on the shaft a sufficient distance from the disk 29 to permit the pawl 51 and all parts associated with it to pass the lever without touching it. But the free end of the lever is provided with a laterally extending lug or tooth 85

65. In Figure 3 a portion of the lever is broken away, leaving the tooth 65 in its normal position. Extending outwardly from the pawl 51 is a lug, or tooth 66, this lug being 90 in the same vertical plane as lug 65. When the pawl 51 is in its normal position, that is, when its tail 54 is engaged with the pin 55, it will impinge on the lug 65 when the crank 95 is operated and rock the lever 60. This throws the hook 64 into the path of the stud 31, which arrest the crank when the stud impinges on the hook. This is what has occurred in Figure 2. When a coin of sufficient diameter is in the carrier, as in Figure 100

1, turning the crank causes the coin to wipe past the end of the screw 58, the coin being compelled to do this by the washer which surrounds the pivotal screw 52 behind the pawl. The screw 58, which I will hereinafter refer 105

to as the abutment, is so adjusted that in wiping past the abutment the coin, bearing against the lug 56, will rock the pawl far enough on its pivot to permit the lug 66 to 110 pass the lug 65 without touching it. This is illustrated in Figure 3.

The lug 66 having passed the lug 65 without touching it, the lever 60 and locking member 62 remain stationary in the position they 115 occupy in Figures 1 and 3, and the crank is permitted to continue its movement and actuate the mechanism as previously described.

A full-stroke device, not shown in Figs. 1, 2 and 3, takes control of the shaft after it has 120 passed the position it occupies in Fig. 2, and compels the shaft to turn clockwise the required distance before permitting it to return, and then requiring it to return entirely 125 home before it may begin another cycle of operation. The full-stroke device must not

130

take control before the shaft reaches the point where it may be arrested, as in Figure 2. The timing of the full-stroke device will be considered more at length in connection with the improved mechanism.

I shall now describe the mechanism for registering and disposing of coins according to their character. Between the plates 57 a lever 70 is mounted to rock on a fixed axis, 71. 10 In Figure 3 one of the plates is removed, showing the lever in full lines. At its lower end this lever carries a stud 72, which extends through a notch cut in one of the plates 57 and plays in a slot 62^a in the lower end of the 15 lever 62. When the lever 62 is in its normal position, as in Figure 3, the lever 70 is in the position it occupies in that figure. When a coin has passed the abutment, assuming that it is of sufficient size to secure the passage of 20 lug 66 past lug 65, the coin passes along the right hand side of lever 70, as in Figure 3, and lights on a stud 73 which is carried by the operating arm of a counter. The coin is shown with dotted lines supported by the 25 lever 70 and stud 73. An arm 75, fixed to a small shaft 76, has a slot at its free end. A stud 77 carried by an arm depending from a sliding member 78 plays in this slot, and when the member 78 moves horizontally to 30 the right the arm 75 is rocked clockwise. By means not shown, and which it is not necessary to describe, the member 78 is moved to the right at each clockwise motion of the crank and to the left upon the return stroke 35 of the crank. Fixed to the shaft 76 is a second arm, 79, having a slot and pin connection to a sliding member 80, which is confined between the plates 57, and each time the arm 75 is rocked as above described the member 80 40 is moved down and up. The movements are so timed that the coin lodges on the counter stud 73 before member 78 moves. The sliding member 80 impinges on and pushes the coin down between the lever 70 and stud 73, with 45 the result that the arm carrying the stud is rocked on its axis. Shortly after the coin has been pushed past the stud the beveled end of the sliding member 80 engages the stud and continuing its downward movement the slide 50 rocks the counter arm back to its original position. And thus a coin which secures the release of the crank, or to be more exact, a coin which prevents the arrest of the crank is registered on the counter. The counter operating mechanism is all shown in dotted lines in 55 Figures 1 and 3, but it is very clearly shown. Having passed the counter stud the coin drops into the cash box 81.

As is shown in Figure 2, movement of the 60 locking member 62 to the position for arresting the crank, throws the lever 70 to a position where a coin dropping between the plates 57 will descend on the left hand side of the lever and is conducted to the chute 82 (Figure 65 1). When the hood is on the machine this

chute registers with a small receiver set in the side of the hood and coin dropping into this receiver is accessible to the customer. In order to reduce as much as possible the opportunity for operating the machines with other 70 than a good coin, the abutment screw 58 may be set so that any coin even slightly below the standard size will fail to get the lug 66 past the lug 65. This arrangement may result occasionally in a good coin being rejected, but 75 since the coin is returned to the prospective customer this is not a serious matter.

I shall now proceed to describe the improved mechanism, referring first to Figure 4, which shows the parts in their normal positions. The crank 32 is not shown, but it is to be understood that it is fixed to shaft 28. The pump (not shown) is operated by a rack 26 and gear 27, the latter being loosely mounted on the shaft 28 as before. Rigidly fixed to 80 the shaft 28 is a cam 100, taking the place of the disk 29 in the old construction, the cam having an arcual slot 30 in which a stud 31 in the gear plays, as before. A locking member 101, mounted to rock on a stationary center 85 90 95 102, is arranged to arrest the crank when it is operated without a coin having been inserted in the slot, or in case the coin is too small. The mechanism for this purpose will now be described:

Mounted on the superbase 34 is a frame 105, which carries a pair of plates 106 and 107, the latter being circular and provided with a laterally extending annular flange 108, converting the plate 107 into a sort of housing. See Figs. 6 and 12. A disk 109 is mounted to rotate in this housing, it being provided with a laterally extending stud 110 which is journaled in the plates 106 and 107, and the frame 105, a cotter pin 111 being inserted in the end 100 105 110 115 of the stud. A lever 112 fulcrumed on a stationary pivot 113 carried by the frame 105, is connected at its upper end to the disk 109 by a link or pitman 114. At its lower end the lever carries a roller 115 which normally lies in a deep recess formed in the periphery cam 100. See Figure 4. When the shaft 28 is rotated the left hand side, 116, of said recess acts as a cam and rocks the lever, the roller riding up the cam to the first step, 117, as in Fig. 7. The step 117 is concentric and permits the cam to rotate a short distance without moving the lever; then a second cam, 118, engages the roller and rocks the lever still farther, raising the roller to the second step, 115 120 125 which is the concentric perimeter 119 of the cam. The pitman 114 is connected to the disk 109 in such a way that rocking the lever 112 rotates the disk.

A rectilineal plate 125 is arranged to slide 125 radially in a suitable guide formed in the disk 109, the outer end of which plate is bent to form a right angle, the bent over end carrying a small block 126, which I will hereinafter refer to as a "pawl." A stud 127 is fixed in 130

the plate 125 in the vicinity of the axis of the disk and extends through a slot 128 in the disk; a spring 129 carried by the disk bears on this stud and constantly presses the pawl 126 toward the flange 108. Normally the pawl lies quite close to this flange, as in Figure 4, the flange being partially cut away to allow the plate to cross it. As the plate moves with the disk when it rotates, the flange is cut for 10 approximately one-third of the circumference of the disk. See figure 12.

A lever 130 is loosely mounted on the stud 110 between the frame 105 and plate 106 (see Fig. 6), one end of which lever, 131, is bent to 15 form a right angle, thereby bringing it into the plane in which the pawl 126 moves; it is also in the zone in which the pawl moves when in its normal position with reference to the disk; that is, in the position shown in 20 Figs. 4 and 5. At a point 132 a rod 133 is attached to the lever 130, by which the lever is connected to the locking member 101. It will now be seen that when the shaft 28 is rotated clockwise the lever 112 will be rocked by the 25 cam 116, from the position it occupies in Fig. 4, causing the disk 109 to be rotated, the pawl 126 moving with the disk. A comparatively slight movement of the shaft is sufficient to rotate the disk to where the pawl 126 30 will impinge on the end 131 of the lever 130, and continued movement of the shaft causes the pawl to rock the lever. Through the medium of the rod 133 the locking member 101 is rocked and its hooked end is thrown 35 into the path of movement of the stud 31 carried by the gear. The movement of the parts is so timed that by the time the end of the slot 30 impinges on the stud the hook is in position to prevent movement of the gear and the 40 movement of the shaft is thus arrested by the stud bearing against the hook of the locking member. This is what has occurred in Figure 5.

I will now describe the mechanism whereby 45 a coin of proper size moves the pawl 126 outward, so that it will pass the end 131 of the lever without touching it, as in Figs. 9 and 10. The disk 109 is provided with a pocket 140 for the reception of a coin. When the disk is in 50 its normal position the open end of the pocket faces and is quite close to the wall of the hood. This is best shown in Figure 12, where the the hood is indicated by the line 141. Attached to the hood is an escutcheon plate 142, having 55 a slot 143 opposite the coin receptacle 140. The plate 106 carries a flange 144, which is folded over at its outer edge to form a guide for a shutter 145, used to close the coin slot when the reservoir is empty. At 146 the 60 flange 108 is cut away sufficiently to allow a coin to be inserted in the receptacle. See also Fig. 4. The portion of the flange from the cut-away 146 to the point 147 forms an abutment 148, against which the coin wipes as the 65 disk rotates, from which point the flange is

cut away so that after the coin has passed the abutment it may leave the receptacle 140. Referring to Fig. 4 it will be seen that one edge of the coin 149 in the receptacle lies against the end of the plate 125, while the 70 opposite edge extends beyond the zone in which the abutment lies. Therefore, when the coin impinges on the corner of the abutment, early in the movement of the disk, it is pushed deeper into the receptacle, and being against the end of the plate 125 it moves the plate outward. If the coin is of sufficient diameter the pawl 126 will thus be moved far enough to cause it to pass outside of the end 131 of the lever 130. The lever 130 and locking member 101 being undisturbed, the shaft 28 is permitted to complete its normal cycle of operation, and perform the various functions allotted to it. If the diameter of the coin is insufficient to move the pawl far 80 enough to pass the lever 131, the lever is moved by the pawl just as though no coin had been deposited in the receptacle, with the result that the locking member 101 is brought into action and the movement of the shaft 85 is arrested, in the manner previously described. The pawl 126 is attached to the plate 125 with screws 150 and an opposing set screw 151, by means of which the position of the pawl with reference to the plate can be 90 varied. By means of this adjustment a certain minimum for the diameter of a coin necessary to secure the operation of the machine may be established and a coin of less diameter will then fail to secure its operation. 100

Coins which secure the operation of the machine; in other words, acceptable coins, are conducted to a cash box 155, by means of a chute 156. Above the superbase 34 the chute comprises a part 157 of the frame, a plate 158 secured thereto with screws, and a plate 159, hinged at 160 to the part 157. It is to be understood that the plates 158 and 159 are sufficiently removed from the frame 157 to permit the coins to pass between them. To 110 prevent rejected coins, that is, coins which do not secure the operation of the machine, from entering the coin chute, the plate 159, which will be called the deflector hereinafter, is provided with a laterally extending bifurcated wing 161, in which plays an extension 162 of the lever 130. When the lever 130 is rocked because of the coin being too small in diameter, the deflector is rocked on its axis by the extension 162, to the position shown in Fig. 115 6. Then when the coin drops out of the receptacle it is deflected from the main coin chute to a return chute 163. See also Fig. 5 where the operation of the deflector is illustrated. In Figs. 4 and 5, a portion of the 120 cover of the return chute is broken away to make the construction more clear.

A full-stroke device is arranged to come into action, or take control, as I prefer to express it, after the shaft 28 has passed the 125

point at which it might be arrested by the locking member 101. It comprises a toothed segment 165 secured to the shaft 28 and a spring actuated pawl 166 to co-operate with the teeth of the segment. As the device is well illustrated in Figs. 4, 5 and 7, and is of an old and well known type, it need not be further described here. The full-stroke device is so timed that it cannot take control until after the shaft has passed the point at which it is liable to be arrested by the locking member 101. When the shaft 28 is near its normal or home position as in Fig. 4, it is urged toward said home position by a spring 167, one end of which is attached to the frame 33 and the other to the lever 112. As this spring tends to move the lever to its normal position, the roller bearing against the cam face 116 acts to turn the shaft counter-clockwise. But on the other hand, the return of the lever 112 and its associated parts to their normal position does not depend upon the spring. A horn 168 projecting from the cam 100 engages the roller and returns the lever 112 to its normal position. By referring to Fig. 1 it will be seen that the crank is in such a position when at home that its weight tends to return the shaft to its home position.

It is important to prevent the coin leaving the receptacle 140 until after the full-stroke device assumes control, as it is then impossible for the purchaser to lose his coin and fail to obtain his purchase from the machine.

For this purpose a laterally extending ear 170 is carried by the deflector 159. This ear, or retainer, is seen in plan in Fig. 6, but its function is best illustrated in Fig. 7. In that figure the full-stroke device has just taken control; that is, the pawl 166 has just dropped behind the first tooth of the segment 165, while the coin is still held in the receptacle by the retainer 170. The lever roller is resting on the step 117 and the cam 118 has not yet reached the roller; so the disk 109 is stationary and has been since the roller ran onto the step 117. The cam 118 will rock the lever and rotate the disk far enough to carry the coin past the retainer. In Fig. 5 the coin having been rejected because of its insufficient size, is enabled to drop from the receptacle because the movement of the deflector by the extension 162 has removed the retainer from the plane of the receptacle.

While coins will usually drop from the receptacle by gravity, I provide an ejector by which they are ejected positively. This consists of a lever 175 pivoted to the disk 109, having a lateral lug 176 which plays in a slot 177 in the disk, the lug extending across the coin receptacle 140. The end of the plate 125 is bifurcated and in Fig. 4 it is seen that the purpose of this is to provide for the retirement of the lug 176 to allow the coin to impinge directly upon the end of the plate. De-

pending from the pitman 114 is a finger 178, adapted to impinge on the ejector as the roller rises from the step 117 to periphery 119 of the cam and during this latter stage of the movement of the lever and disk swing the ejector toward the periphery of the disk, forcibly ejecting the coin if it does not drop out of the pocket by gravity. A finger 179 projecting laterally from the ejector is first engaged by the side of the finger 178, as in Figs. 7 and 10, which produces a comparatively slow movement of the ejector. During the second stage of the movement of the pitman and disk the end of the finger 178 engages the ejector directly and throws the coin out quickly. When a coin of insufficient diameter is inserted the movement of the shaft 28 is arrested before the pitman and disk have moved sufficiently to actuate the ejector. The ejector is then actuated by a horn 180 which projects from pivotally mounted plate 181. This plate carries another horn, 182, whose end is confined between the deflector 159 and an ear 183 carried by the deflector. When the deflector is thrown to the position it occupies in Figs. 5 and 6, the plate 181 is moved with it bringing the horn 180 into the plane of movement of the ejector. Coming into engagement with the horn 180 the ejector is moved to eject the coin, as in Fig. 5. When the coin is of sufficient size and the deflector remains in normal position, the ejector passes behind the horn 180, as in Figs. 10 and 11.

The mechanism for operating the counter is best shown in Figs. 7 and 8. The counter itself is not shown in either of these views but the shaft on which the counter wheels are mounted is shown in section at 190. Fixed to this shaft is an arm 191, carrying a stud 192 which extends into the coin chute, normally standing in the position shown in Fig. 7, through the action of a spring 193. When a coin drops into the chute it is arrested by the stud, as shown with dotted lines in Fig. 7. Pivoted mounted on the frame 157 is a lever 194, which is provided with a laterally extending arm 195. This arm is in the path of the rack 26, the upper rear corner of which is rounded, and as the rack rises it engages the arm and rocks the lever from the position shown in Fig. 7 to that it occupies in Fig. 8, pushing the coin before it. In its passage the coin rocks the arm 191 and actuates the counter, the spring 193 returning the arm to its normal position. The lever 194 is returned to its normal position by a spring, but to insure its return the laterally extending arm 195 is provided with a depending lobe 197 which, as the rack descends, is engaged by a stud 198 projecting from the side of the rack remote from the observer as seen in the several views.

While the mechanism is enclosed in a hood

or casing which prevents access to it, the caretaker is enabled to remove the hood for inspection and to clean or oil the parts. Inspectors or caretakers of such machines 5 commonly carry slugs with which to test the mechanism. But these would operate the counter, which would then show an incorrect record of coins received. To avoid this the caretaker can trip the mechanism manually when the hood is off. In the structure 10 shown in Figs. 1, 2 and 3 he swings the coin carrier with his finger while he moves the crank. Thus he can cause the tooth 66 to pass the tooth 65, as in Fig. 2. In the im- 15 proved structure he needs only to push the pin 127 to the right far enough to enable the block 126 to pass lever end 131.

It will now be seen that the apparatus 20 above described is not only positive in its operation and free from parts or combinations of parts which are liable to get out of order, but that it is to a marked degree what is called "fool proof". In at least two particulars it is a departure from other coin 25 controlled vending devices, as it employs novel methods of effecting certain results. First, it is novel to utilize movement of the operating member of a vending machine to actuate mechanism whereby movement of 30 the operating member is arrested before vending occurs, unless a suitable coin has been deposited in a receptacle, and the term "vending" is here used in a broad sense, to include any coin controlled apparatus. Sec- 35 ond, it is novel to register coins received in a vending machine by means of the coins themselves as they pass to the coin box.

While I have disclosed two structures for carrying out my method of controlling 40 vending machines it is not to be understood that I regard these as the only ones by which it can be done; nor do I wish it understood that I consider the scope of my invention limited to the particular details of construction shown. The scope of my invention 45 is only limited by the claims appended hereto. What I claim is as follows:

1. In a controlling mechanism for dispensing and other devices, a member adapted 50 to operate the controlled device, a coin carrier moved by said member, a locking device adapted to arrest the operating member; and a member intermediate the coin carrier and said locking device, adapted to be en- 55 gaged by the carrier when the operating member is moved without a coin in the carrier and caused to move the locking member into position for arresting the operating member.

60 2. In a controlling mechanism for dispensing and other devices, a member adapted to operate the controlled device, a coin carrier moved by said member, a pawl mounted on the carrier, a lever which is engaged by 65 the pawl and rocked when the carrier is

moved without carrying a coin, or if it carries a coin of insufficient size; a locking device adapted to arrest the operating member, a connection between said lever and locking device whereby the latter is made to 70 arrest the operating member when the lever is rocked by the pawl, and means whereby the presence in the carrier of a coin of required proportions prevents engagement of the pawl with the lever. 75

3. In a controlling mechanism for dispensing and other devices, a member adapted to operate the controlled device, a coin carrier moved by said member, a pawl mounted on the carrier, a lever which is engaged by 80 the pawl and rocked when the carrier is moved without carrying a coin, or if it carries a coin of insufficient size; a locking device adapted to arrest the operating member, a connection between said lever and locking device whereby the latter is made to 85 arrest the operating member when the lever is rocked by the pawl, and a relatively stationary abutment whereby as the carrier moves the pawl is displaced through the me- 90 dium of a coin of required proportions stationed in the carrier, so the pawl will pass the lever without moving it.

4. In a controlling mechanism for dispensing and other devices, a member adapted to 95 operate the controlled device, a coin carrier moved by said member, a pawl mounted on the carrier, a lever which is engaged by the pawl and rocked when the carrier is moved without carrying a coin, or if it carries a 100 coin of insufficient size; a locking device adapted to arrest the operating member, a connection between said lever and locking device whereby the latter is made to arrest the operating member when the lever is rocked 105 by the pawl, means whereby the presence in the carrier of a coin of sufficient size prevents engagement of the pawl with the lever, two coin chutes to receive coins as they leave the carrier, and means for directing coins to one 110 chute or the other according to whether they are or are not large enough to prevent the arrest of the operating member. 115

5. In a controlling mechanism for dispensing and other devices, a member for operating the controlled device, a coin carrier moved by said member, a locking device adapted to arrest the operating member, a pawl mounted on the carrier, a lever which is engaged by the pawl and rocked when the carrier is moved without carrying a coin, or if it carries a coin of insufficient size, said lever being adapted 120 to operate the locking device and cause it to arrest the operating member; and a relatively fixed abutment past which the coin wipes as the holder moves, whereby through the medium of a coin of sufficient size stationed in the holder the pawl is displaced so it will pass the lever without moving it, the abutment serving to retain the coin in the holder until 125 130

the pawl has passed the lever, after which the coin is permitted to fall from the holder.

6. In a controlling mechanism for dispensing and other devices, a member for operating the controlled device, a coin carrier moved by said member, a locking device adapted to arrest the operating member, a pawl mounted on the carrier, a lever which is engaged by the pawl and rocked when the carrier is moved without carrying a coin, or if it carries a coin of insufficient size, said lever being adapted to operate the locking device and cause it to arrest the operating member; and a relatively fixed abutment past which a coin of sufficient size stationed in the holder wipes as the holder moves, said abutment acting as a retainer to keep the coin in the holder until the pawl has passed the lever or engaged and started to move it, according to whether the coin is or is not of sufficient size.

7. In a controlling mechanism for dispensing and other devices, a member for operating the controlled device, a coin carrier moved by said member, a locking device adapted to arrest the operating member, a pawl mounted on the carrier, a lever which is engaged by the pawl and rocked when the carrier is moved without carrying a coin, or if it carries a coin of insufficient size, said lever being adapted to operate the locking device and cause it to arrest the operating member; a relatively fixed abutment past which a coin of sufficient size stationed in the holder wipes as the holder moves, said abutment acting as a retainer to keep the coin in the holder until the pawl has passed the lever or engaged and started to move it, according to whether the coin is or is not of sufficient size, and means for ejecting the coin from the holder after it has past the abutment.

8. In a coin controlled mechanism, an operating member therefor, a receptacle for a coin, means whereby a suitable coin stationed in said receptacle enables the controlled mechanism to be operated by the operating member, a counter, and means depending upon a coin having enabled the operating member to be actuated, but independent of the weight of the coin, whereby the counter is actuated to show that the controlled mechanism has been operated.

9. In a coin controlled mechanism, an operating member therefor, a receptacle for a coin, means whereby a suitable coin stationed in said receptacle enables the controlled mechanism to be operated by the operating member, a counter, and means in which the coin is an element, whereby the counter is actuated by the operating member, and means whereby the coin is prevented from actuating the counter unless the coin also performs its first mentioned function.

10. In a coin controlled mechanism an operating member therefor, a receptacle for a coin, means whereby a suitable coin stationed in

said receptacle enables the controlled mechanism to be operated by the operating member, a counter, a coin chute, and an operating member for the counter, said member extending into the chute so that it is engaged by the coin and the counter operated as the coin traverses the chute, and means actuated by said first mentioned operating member for pushing the coin past said counter operating member, thereby actuating the counter.

11. In a coin controlled mechanism, an operating member therefor, a receptacle for a coin, means whereby a suitable coin stationed in said receptacle enables the controlled mechanism to be operated by the operating member, a chute to receive the coin after the operation of the controlled mechanism is assured, a counter having an operating member which extends into the chute so that as the coin passes said member it will be moved to register the passage of the coin on the counter, and means actuated by said first mentioned operating member for pushing the coin past the counter operating member.

12. In a controlling mechanism for dispensing and other devices, a member for operating the controlled device, a coin carrier moved thereby, a locking device adapted to arrest the operating member, means whereby said locking device is actuated to arrest the operating member when said member is moved without a coin of sufficient size being in the coin holder, two chutes adapted to receive the coin after it has functioned in the holder, means for directing a coin to one chute or the other according to whether the coin is of sufficient size to prevent arrest of said operating member, a counter, and means for registering thereon all coins which are directed to one of the chutes.

13. In a coin controlled device, a manually operable member and associated mechanism requiring the agency of a coin having certain qualifications to enable said member to accomplish its ultimate purpose, a receptacle for the coin, two coin chutes, one to receive coins which enable said operating member to perform its ultimate purpose, the other to receive coins which are deficient, means for ejecting the coin from said receptacle and means for directing it into one or the other of said chutes.

14. In a coin controlled device, a manually operable member and associated mechanism requiring the agency of a coin having certain qualifications to enable said member to accomplish its ultimate purpose, a receptacle for the coin, two chutes, one to receive coins which enable said member to function, the other to receive coins which are deficient, means for positively ejecting the coin from said receptacle, means for directing it to one or the other of said chutes according to whether or not the coin has been deficient,

and means for registering the coins which are directed into one of said chutes.

15. In a controlling mechanism for dispensing and other devices, a member adapted to operate the controlled device, a coin receptacle, locking mechanism whereby to arrest the operating member when it is moved a given distance without a coin of proper proportions present in the receptacle, a full-stroke device for controlling said operating member, said device being adapted to take control only after said member has moved past the point where it may be arrested, means for retaining a coin in the receptacle until after the full-stroke device has taken control, and means for releasing a coin which has failed to prevent the arrest of the operating member.

16. In a controlling mechanism for dispensing and other devices, an operating member therefor, a coin carrier moved thereby, a pawl which is moved when the carrier moves, a lever adapted to be engaged and rocked by said pawl when the operating member is moved while there is no coin in the carrier, a locking device adapted to arrest the operating member, a connection between said device and said lever, whereby when the lever is rocked the locking device is actuated to arrest the operating member; and a full-stroke device for controlling the operating member, said device being adapted to take control only after said pawl has passed the lever without moving it.

35 17. In a controlling mechanism for dispensing and other devices, a member adapted to operate the controlled device, but having a limited degree of lost motion with reference thereto, a coin, receptacle, locking mechanism whereby to arrest the operating member before it has consumed said lost motion, if it is moved while there is no coin in said receptacle or if the coin therein is undersize and therefore too small to function and a full-stroke device for controlling said operating member, said device being adapted to take control only after said member has moved past the point where it may be arrested, means for retaining an undersize coin in the receptacle until after the operating member begins to move, and means operated by said member for ejecting said undersize coin.

55 18. In a controlling mechanism for dispensing and other devices, a member adapted to operate the controlled device, but having a limited degree of lost motion with reference thereto, a coin receptacle, locking mechanism whereby to arrest the operating member before it has consumed said lost motion, if the operating member be moved while there is no coin in said receptacle or if the coin therein is too small, a full-stroke device for controlling said operating member, said device being adapted to take control only

after said member has moved past the point where it may be arrested, means for retaining the coin of sufficient size in a receptacle until after the full-stroke device takes control, a chute to receive the coin when it leaves the receptacle, a second chute, and means for diverting coins to said second chute when they are too small to prevent arrest of the operating member.

19. In a controlling mechanism for dispensing and other devices, a revoluble disk, a receptacle thereon for a coin, a pawl carried by the disk, an abutment past which a coin in the receptacle wipes as the disk rotates, the coin being thereby pressed toward the axis of the disk and in doing so moving the pawl; a lever having an arm which is engaged by the pawl in case the disk is rotated without a coin in the receptacle, or if the coin is too small to move the pawl sufficiently to permit it to pass the arm without touching it; a crank whereby the disk is rotated, a locking member adapted to arrest the crank, and a connection between said locking member and lever, whereby the locking member is actuated to arrest the crank when the lever is rocked by the pawl.

20. In a controlling mechanism for dispensing and other devices, a revoluble disk, a receptacle thereon for a coin, a pawl carried by the disk, an abutment past which a coin in the receptacle wipes as the disk rotates, the coin being thereby pressed toward the axis of the disk and in doing so moving the pawl; a lever having an arm which is engaged by the pawl in case the disk is rotated without a coin in the receptacle, or if the coin is too small to move the pawl sufficiently to permit it to pass the arm without touching it; a shaft whereby the controlled device is operated, a cam thereon, a lever, one arm of which bears on the cam, the other arm being connected to and arranged to rotate the disk when the lever is rocked by the cam, a full-stroke device, a member whereby the coin is retained in the receptacle until the full-stroke device takes control to compel completion of the cycle of the shaft, and an ejector whereby the coin is ejected from the receptacle after the full-stroke device takes control.

115 21. In a controlling mechanism for dispensing and other devices, a revoluble disk, a receptacle thereon for a coin, a pawl carried by the disk, an abutment past which a coin in the receptacle wipes as the disk rotates, the coin being thereby pressed toward the axis of the disk and in doing so moving the pawl; a lever having an arm which is engaged by the pawl in case the disk is rotated without a coin in the receptacle, or if the coin is too small to move the pawl sufficiently to permit it to pass the arm without touching it; a two-step cam and means for moving it, a lever operated by said cam and connected to the disk so as to rotate the disk when the cam

moves, the disk being thereby rotated in two stages, a full-stroke device adapted to take control between said stages and compel the completion of the cycle of operation of the mechanism, and a member whereby to retain the coin in the receptacle until the full stroke device has taken control, the second stage of the disk's movement carrying the coin past said member, so the coin may leave the receptacle.

22. In a controlling mechanism for dispensing and other devices, a revolute disk, a receptacle thereon for a coin, a pawl carried by the disk, an abutment past which a coin in the receptacle wipes as the disk rotates, the coin being thereby pressed toward the axis of the disk and in doing so moving the pawl; a lever having an arm which is engaged by the pawl in case the disk is rotated without a coin in the receptacle, or if the coin is too small to move the pawl sufficiently to permit it to pass the arm without touching it; a two-step cam and means for moving it, a lever operated by said cam and connected to the disk so as to rotate it when the cam moves, the disk being thereby rotated in two stages, a full-stroke device adapted to take control between said stages and compel the completion of the cycle of operation of the mechanism, provided the aforesaid pawl has not engaged the lever, a member whereby to retain the coin in the receptacle until after the full stroke device has taken control, and means for releasing a coin from the receptacle in case said coin is too small to move the pawl far enough to clear the lever.

23. In a controlling mechanism for dispensing and other devices, a revolute disk, a receptacle thereon for a coin, a pawl carried by the disk, an abutment past which a coin in the receptacle wipes as the disk rotates, the coin being thereby pressed toward the axis of the disk and in doing so moving the pawl; a lever having an arm which is engaged by the pawl in case the disk is rotated without a coin in the receptacle, or if the coin is too small to move the pawl sufficiently to permit it to pass the arm without touching it; an operating member, means for rotating the disk thereby, means operated by said lever when it is moved by said pawl, whereby to arrest the operating member after it has moved a given distance, a full-stroke device adapted to take control and compel the operating member to complete its cycle of movement, provided the operating member has not been arrested, means for retaining a coin in the receptacle until after the full-stroke device takes control, and means for releasing a coin of insufficient size.

24. In a controlling mechanism for dispensing and other devices, a revolute disk, a receptacle thereon for a coin, a pawl carried by the disk, an abutment past which a coin in the receptacle wipes as the disk rotates,

the coin being thereby pressed toward the axis of the disk and in doing so moving the pawl; a lever having an arm which is engaged by the pawl in case the disk is rotated without a coin in the receptacle, or if the coin is too small to move the pawl sufficiently to permit it to pass the arm without touching it; an operating member, means for rotating the disk thereby, means operated by said lever when it is moved by said pawl, whereby to arrest the operating member after it has moved a given distance, a full-stroke device adapted to take control and compel the operating member to complete its cycle of movement, provided the operating member has not been arrested, means for retaining a coin in the receptacle until after the full-stroke device takes control, means for releasing a coin of insufficient size and means for positively ejecting all coin from the receptacle.

25. In a coin controlled device, a manually movable operating member and associated mechanism requiring the agency of a coin having certain qualifications to enable said member to accomplish its ultimate purpose, a receptacle for the coin, an inlet thereto, two coin chutes, one to receive coins which qualify, the other to receive disqualified coins, means operated by said operating member for ejecting the coin and directing it into one or the other of said chutes, said means requiring further movement of the operating member to eject qualified than disqualified coins, and a full stroke device adapted to take control and compel a full stroke of the operating member after said member has passed the point where disqualified coins are ejected, but before it has reached the point where qualified coins are ejected.

26. In a coin controlled device, a manually movable operating member and mechanism requiring the agency of a coin having certain qualifications to enable said member to accomplish its ultimate purpose, a receptacle for the coin, two coin chutes, one to receive qualified coins, the other to receive disqualified coins, means operated by said operating member for ejecting a coin and directing it into one or the other of said chutes, said means requiring further movement of the operating member to direct the coin into the chute for qualified coins than to direct it into the chute for disqualified coins, a full stroke device adapted to take control of the operating member after said member has moved far enough to eject a disqualified coin but before it has moved far enough to eject a qualified coin, and means for registering the qualified coins after the full stroke device takes control.

27. In a controlling mechanism for dispensing and other devices, a revolute coin carrier having a receptacle into which to deposit a coin, an operating member for the controlled device, a pitman connecting said

member to the carrier, whereby the carrier is rotated a given distance when the operative member is actuated and the coin carried to a chute, and an ejecting device mounted on the carrier, said device being engaged by the pitman and the coin positively ejected from the receptacle into the chute.

28. In a controlling mechanism for dispensing and other devices, an operating member, a locking member, means whereby movement of the operating member connects the locking member to it, so by continued movement the operating member moves the locking member, said means comprising two teeth, one of which is connected to the operating member and the other to the locking member, the former being adapted to impinge on and thereafter move the latter, causing the locking member to function, and means 10 under the control of the operator for causing the moving tooth not to engage the other,

thereby avoiding actuation of the operating member.

29. In a controlling mechanism for dispensing and other devices, an operating member, a locking member, means whereby movement of the operating member connects the locking member to it, so by continued movement the operating member moves the locking member into position to arrest the operating member, said means comprising two teeth, one of which is connected to the operating member and the other to the locking member, the former being adapted to impinge on and thereafter move the latter, causing the locking member to function, and means comprising a coin, for causing the former tooth to pass the latter without engaging it, thereby allowing the operating member to move without interference.

ROLLYN H. BAKER.
